US0D1083377S

(12) **United States Design Patent** (10) **Patent No.:** **US D1,083,377 S**
(45) **Date of Patent:** **** Jul. 15, 2025**

(54) **FOLDING TRUNK**

(71) Applicant: **Shanghai Neoent Industrial Co., LTD.**, Shanghai (CN)

(72) Inventors: **Xiaofeng Mou**, Shanghai (CN); **Simao Liu**, Shanghai (CN); **Jianglong Chen**, Shanghai (CN); **Jinquan Yang**, Shanghai (CN); **Daiping Jiang**, Shanghai (CN)

(73) Assignee: **Shanghai Neoent Industrial Co., LTD.**, Shanghai (CN)

(**) Term: **15 Years**

(21) Appl. No.: **29/895,033**

(22) Filed: **Jun. 16, 2023**

(30) **Foreign Application Priority Data**

Jan. 29, 2023 (CN) 202330018567.1

(51) **LOC (15) Cl.** **03-01**

(52) **U.S. Cl.**

(57) **CLAIM**

The ornamental design for a folding trunk, as shown and described.

DESCRIPTION

FIG. 1 is a perspective view of a folding trunk showing our new design;

FIG. 2 is a front view thereof;

FIG. 3 is a rear view thereof;

FIG. 4 is a left side view thereof, a right side view being a mirror image of the left side view;

FIG. 5 is a top view thereof;

FIG. 6 is a bottom view thereof; and,

FIG. 7 is a perspective view thereof in an unfolded configuration, the other side of the unfold configuration being a mirror image of the perspective view shown in FIG. 7.

The broken lines depict portions of the folding trunk that form no part of the claimed design.

1 Claim, 7 Drawing Sheets
